UNITED STATES PATENT OFFICE.

ELIAS F. SPROSS, OF OKEMOS, AND PHILo R. WOODWORTH, OF LANSING, MICHIGAN.

RAIL-TIE.

992,283.

Specification of Letters Patent. Patented May 16, 1911.

Application filed January 30, 1911. Serial No. 605,437.

To all whom it may concern:

Be it known that we, ELIAS F. SPROSS and PHILo R. WOODWORTH, citizens of the United States, residing at Okemos and Lansing, respectively, county of Ingham, State of Michigan, have invented certain new and useful Improvements in Rail-Ties; and we do hereby declare the following to be a full, clear, and exact description of the invention, such as will enable others skilled in the art to which it appertains to make and use the same.

This invention relates to cross ties for rail-ways, and especially to ties that consist for the most part of concrete or other suitable plastic material which may be reinforced in any appropriate manner.

The invention has particular reference to the means for securing the rails to ties of this general character, and the object in view is to provide rail securing means which can be easily and quickly placed in assembled relation with respect to the rail and tie and which lock the rail firmly in place, although the rail may be easily removed from its position on the tie when such is desired.

The construction has the characteristic advantage that the rail is clamped in place by simple devices which are readily accessible, easily placed in and removed from operative position without modifying the tie structure, and which are replaceable with considerable facility when wholly or partially worn out.

With these ends in view the invention consists in the novel features and combinations of parts to be hereinafter described and finally recited in the claims.

In the accompanying drawing: Figure 1 is a side elevation partly in vertical section of a rail tie embodying our invention, Fig. 2 is a top plan view of the parts shown in Fig. 1, Fig. 3 is a vertical transverse section through the tie; and Figs. 4, 5 and 6 are detail perspective views of different parts of the rail securing means.

Referring to the drawing, 10 indicates a cross tie of reinforced concrete, but it will be understood that although our invention is primarily designed for use in connection with ties of that character, the invention is not limited to this feature.

The tie 10 illustrated in the drawing may be reinforced in any suitable manner, but we prefer to provide the same with reinforcements in the form of longitudinally

extending angle bars 11, 12, which may be conveniently arranged at the corners of the tie, as illustrated in Fig. 3. At the respective ends of the tie, where the rails are to be secured in place, the tie is provided with median vertical openings or slots 13 that are open at the top and bottom surfaces of the tie or sleeper and which are somewhat longer than the width of the rail base. The width of these openings or slots is more or less immaterial but we prefer to have them correspond approximately in width to the shank of an ordinary rail spike. As shown in Fig. 3, the slots 13 are arranged midway between the individual reinforcing bars 11, 12 of the respective pairs of such bars, and it is obviously expedient to have the reinforcing means extend at opposite sides of said slots, irrespective of the character of such means. Each slot 13 is provided with a metallic lining 14, which is formed as a permanent part of the tie structure in the course of manufacture. The lining 14, which is of box-like form, as shown at the right of Fig. 1, and extends throughout the height of its slot 13, is preferably made integral with or suitably secured to a top plate 15 shown in detail in Fig. 6, which top plate has its upper surface flush with the main body of the tie at the upper part of the latter and thereby serves as a bearing surface for the rail base, across which the latter extends to the full width of the tie, as shown in Fig. 2. It will be understood, however, that both the width and the length of this top plate 15, with respect to the tie, may be varied as called for by conditions.

We prefer to construct both the lining 14 and the top plate 15 of suitable sheet metal, and although the form of the top plate may be widely varied we prefer to construct it in a special manner shown in Fig. 6. Referring to that figure, it will be seen that the plate 15 is provided with downturned corners 16 which are embedded in the concrete in the course of constructing the tie proper and which thereby lock the top plate in the tie. These downturned corners or tangs are especially useful in preventing absolutely all lateral shifting of the plate. A slot 17, closely corresponding in shape with the slot 13 of the tie, is cut out of the median portion of the plate 15, when that plate is formed of sheet metal, and so located as to overlie the aforesaid tie slot. It is desirable to form the top plate of sheet

metal, not only because it can be readily operated upon in the manner indicated but also because the metal or stock struck up from the plate in forming the slot 17 can be 5 folded back to form laterally directed arms or branches 18 which extend from the plate at opposite ends and are provided at the ends with downturned flanges 19 which are embedded in the concrete in substantially 10 the same manner as the tangs 16. Obviously by twisting the metal at the connected ends of the arms 18, viz., at the points where said arms are joined with the margins of the plate body, said arms can be caused to 15 project laterally in the plane of the plate, with their upper surfaces flush with that of the plate, as shown. It will be readily understood that this result may be obtained by cutting the side edges of the slot 17, cutting 20 in half the stock at the middle of said slot and then bending up and then downward and outward the two arms (18) so formed, the flanges 19 being formed on said arms before, during or after this bending 25 operation. This part of the construction may, however, be widely varied, as hereinbefore intimated.

We have shown the rails at 20, and it will be seen that where the base flange of each 30 rail passes over the slot in the lining 13 it is supported on a block 21, preferably of metal, which is detachably held in the tie slot by means of a cross bolt 22, passing through the tie from side to side, preferably 35 at about the middle portion of the box-like lining 14. The block 21 preferably extends throughout the height of the slot 13, as shown, viz., it is co-extensive with said slot in a vertical direction, and the head of the 40 block preferably corresponds in width to the base flange of the rail. As shown in Fig. 1, the fastening bolt 22, on which the block 21, when free, is freely oscillatory lengthwise of the tie, passes through the side portions 45 of the tie, the reinforcing bars 11 and the elongated sides of the tie slot lining in the manner indicated in Fig. 3, from which it will be seen that one end of said bolt is equipped with a nut 23. Obviously the removal 50 of the nut and the bolt from the tie will result in pulling the bolt out of the rail supporting block, which will then be free for removal from the tie slot. The end edges of the block 21 are provided midway of 55 their height with shoulders 21^a which are adapted to be engaged with the enlarged lower ends 24 of rail securing keys 25, the heads of which are fashioned very much like those of ordinary rail spikes and which 60 are designed to fit over the base of the rail in the manner shown in Fig. 1. These locking keys 25 are cut out at the sides and conform to the block 21 and to the rail base in such a manner that when their lower ends 65 24 are engaged with the shoulder 21^a of the

rail supporting block, the inner side edges of said keys will fit securely against the block and against the top surface of the rail base in the manner shown. In order to lock these keys detachably in the position indicated, we employ locking members 26 which are very much like ordinary rail spikes, although their body portions are entirely untapered. These locking spikes are interposed between the keys 25 and the end surfaces of the lining 14, and the parts are of such size and shape that when said locking spikes are forced downward as far as is permitted they will be locked in the tie slot by friction in an effective manner and will 75 at the same time lock the securing keys 25 and the rail in position, as will be readily understood. The rocking of the block 21 on its pivot bolt 22 is of considerable advantage in placing the keys 25 in position, 80 or at least the key first put in place. In order to secure the rail firmly in position it is simply necessary to lay it across the block 21, introduce the keys 25 into the ends of the tie slot, (into which they may enter 90 easily when the locking spikes 26 are removed) and then, after the keys are positioned in the manner indicated in Fig. 1, to pound down the locking spikes 26 in their seats until all of the parts are locked frictionally in a very effective manner. 95

It will thus be seen that the improved rail securing means is of very simple construction, comprises relatively few parts, and can be readily associated with and detached 100 from the tie. It is obviously undesirable to remove the lining 14 and the top plate 15, which are permanent parts of the tie and can be used over and over again with different securing devices of the type described. 105 Owing to the fact that the tie slot 13 is open at the bottom as well as at the top, the interior parts of the rail securing mechanism are accessible, and if the keys 25 or spikes 26 are broken; as by having their heads broken 110 off, said members may be pounded down in the tie slot until they pass out of the lower end of the same, whereupon new securing devices may be placed in position.

In order to hold the rails against spreading or lateral displacement on curves, we use 115 in connection with the rail securing mechanism described, the bracing means shown at the left of Figs. 1 and 2. Referring to those figures, it will be seen that the ends of the 120 bolt 22 are used to secure a stirrup 27 which is made of U shape and comprises an intermediate plate 28 lying on the top surface of the tie at the end portion thereof and equipped with an upstanding flange 29. A 125 detachable rail brace 30 is adapted to be interposed between the flange 29 and the outer surface of the rail web, and we prefer to form this brace of two hinged parts 31, 32, which form a sort of toggle. The sections 130

31, 32 of the toggle brace may be hinged together by means of a pintle 33, and when the brace is in position one end of the section 31 is engaged under the flange or lip 29, previously described, while the opposite end of the part 32 is engaged in the angle between the rail web and the head of the rail, as shown. When the brace is first placed in position it is bent up at the hinge, and it is then tightened by depressing the hinge 10 slightly below the plane in which the toggle sections would be alined, in which position the parts are firmly locked in an obvious manner, with the head of the rail firmly held 15 against lateral and outward displacement.

Without limiting ourselves to the construction shown, we claim:

1. The combination with a rail tie having an elongated slot extending completely therethrough transversely beneath the rail, of a detachable block in said slot on which the rail base is positioned, and means interposed between said block and the walls of said slot to lock the rail in position on said 25 block.
2. The combination with a rail tie having an elongated slot extending completely therethrough and transversely beneath the rail, of a block in said slot, a bolt passing through 30 the tie in a horizontal direction and detachably securing said block in position, a rail lying on the upper surface of the block, rail securing keys overlying the rail base and positively engaged with said block, and 35 means interposed between the walls of said

slot and said keys to lock the latter frictionally in position.

3. The combination with a rail tie having a slot extending therethrough, of a block in said slot, means to mount the block for oscillation, said block having shoulders at its side edges, keys having heads overlying the rail base and provided with enlarged lower ends taking under the shoulders on said block, and frictional means to lock said keys 45 in position in said slot.

4. The combination with a rail tie having a slot, of a lining for said slot, a top plate secured to said lining and lying flush with the upper surface of the tie, a rail supporting block between the lining walls, means to mount said block detachably in position and means interposed between the block and the lining for frictionally locking the rail 50 in position on said plate.

5. The combination with a concrete tie having a slot, and reinforcing members at opposite sides of said slot, of a bolt passing through the tie, the slot and the reinforcing members, a block mounted on said bolt within the slot, and means to clamp the rail base 55 detachably on the upper surface of said block.

In testimony whereof we affix our signatures, in presence of two witnesses.
